UNITED STATES PATENT OFFICE.

FREDERIK NOSSAK, OF NEW YORK, N. Y., ASSIGNOR TO COMPOSITE METAL LATH COMPANY, OF NEW YORK, N. Y., A CORPORATION OF NEW YORK.

MACHINE FOR PRODUCING COMPOSITE-METAL LATHS.

1,398,141.

Specification of Letters Patent.

Patented Nov. 22, 1921.

Application filed June 20, 1914, Serial No. 846,408. Renewed November 6, 1920. Serial No. 422,366.

(GRANTED UNDER THE PROVISIONS OF THE ACT OF MARCH 3, 1921, 41 STAT. L., 1313.)

To all whom it may concern:

Be it known that I, FREDERIK NOSSAK, a subject of the Emperor of Germany, residing at New York city, in the county of New York and State of New York, have invented certain new and useful Improvements in Machines for Producing Composite-Metal Laths; and I do hereby declare the following to be a full, clear, and exact description of the invention, such as will enable others skilled in the art to which it appertains to make and use the same.

My invention relates to machines for producing a composite metal lath such as is illustrated and described in the accompanying drawings and description (see Figures 64-69). The lath is composed of a wire fabric of quadrangular mesh covered on each side with buttons of clay or other suitable material at the junction of the warp and weft wires with openings between the strands of wire so that when the fabric is completed there will be a central wire fabric carrying at all the intersecting points of the strands of wire and at each side of the intersecting points a button of clay or other suitable material, preferably a peculiarly scored or indented button, which is then burned into place producing the composite metal lath, having a wire-fabric carrying on each side a coating of brick sections, resulting in an article which is capable of being manipulated, reeled up or handled in various ways advantageous in the art of building or similar work.

I have spoken of clay as a preferable instance, my machine contemplating the production of a flexible, fire-proof lath whatever the coating employed.

My machine is in two parts which must act synchronously, that is, a part for weaving the wire fabric and a part for applying and fixing the buttons of clay or other material. It is true that there is a third part in the oven in which the lath must be burned to finish it; but the oven may be a separate structure and bears no immediate relation to the other parts of the machine.

I have found, however, in practice, that the wire fabric should pass directly from the weaving machine to the press machine which applies the clay or other material. I have found it impractical or inadvisable to weave the fabric and then reel it up and

apply it to a separate press machine. The buttons of clay or other material must be applied with the greatest nicety and the fabric must come over to the press machine under a uniform tension, with the weft wires tightly drawn into the warp. When the comparatively heavy wire fabric is separately woven the parts do not keep their proper adjustment and the fabric is not in condition to pass through the press-rolls where clay or other material is applied, the wires are pressed together, the whole structure is given the desired regularity of form and finish, and the completed fabric is given its final shape.

In other words it is necessary to maintain throughout the machine a unit arrangement of the fabric so that when the clay buttons are applied they shall each fit precisely upon an intersection or junction of warp and weft wires. In the weaving part of the machine, as will be shown, the weft wire may be accurately placed between the warp wires but it is not necessary or convenient in that mechanism to accurately place the warp wires, that is, in their relative position to each other. I provide that when this fabric with the weft wires placed and with the warp wires not yet accurately distanced the fabric shall take over a feeding roller arranged with precise reference to the press rolls and made to accurately register with the press rolls. When the fabric takes over this feeding roller pyramidal projections enter the meshes of the fabric and accurately pattern the wire fabric so that it shall fit the press rolls. The same scheme is continued through the press rolls from which the fabric proceeds to receive its finishing treatment in other mechanisms. In short, from the beginning of the delivery of the wire fabric from the weaving part to the feeding roller it is necessary or advisable to keep up the precise unit distances and arrangement so that the fabric may be of the proper construction.

I have found, too, that there should be a central power for the two machines and in carrying out my hereinafter described automatic action, that the weaving mechanism should automatically control the action of the press.

This does not mean that the two parts may not run separately; but that to secure the

proper manufacture of this lath it is essential that they should in effect run as one machine and that the wire fabric should pass directly from the weaving part to the 5 press part and that any accident to or failure of the weaving part should not only instantly stop the weaving mechanism but also the part of the machine which applies the coating and which I term, briefly, the 10 press.

I find it convenient in this specification to separately describe the two parts of the machine with occasional reference to the other part in the description of each part.

15 In the drawings illustrating a preferred form of my machine Fig. 1 is a side elevation;

Fig. 2 is a section on the line 2—2 of Fig. 3;

Fig. 17 is a detail view illustrating the manner of connection and operation of the reed or comb;

45 Figs. 18—25 are detail views illustrating the successive operation of a reed upon the warp wires coming from the shuttle, and the placing of the wires;

50 Figs. 26—28 are details illustrating the controlling devices which are operated by the shuttle;

Figs. 29—31 are details illustrating the controlling devices which are operated by the warp wire;

55 Fig. 32 is a side elevation of the press division of the machine;

Fig. 33 is a detail of the circumferential adjuster for determining the profile register of the feeding roller;

60 Fig. 34 is a detail, partly in section, illustrating the means for adjusting the power connection between the two divisions of the machine;

Fig. 35 is a top plan view of the press division of the machine;

Fig. 36 is an end elevation of the press division of the machine;

Figs. 37, 37^a, 38 and 39 are details of the clutch connection and means for operating it;

Fig. 40 is a central vertical section through the press rolls and connected parts;

Fig. 41 is a detail of the cutting or scoring rolls in operation;

Fig. 42 is a sectional detail illustrating the cleaning roller in operation;

Fig. 43 is a section of the operating parts which control the winding reel;

Fig. 44 is a section of the nozzle for feeding in the heating medium for the press rolls;

Fig. 45 is a perspective illustrating the steam feeding mechanism for the cutting and cleaning rollers;

Figs. 46, 47, 48, 49 and 50 are details illustrating the device for feeding the clay or other material to the press rolls;

Figs. 51 and 52 are details illustrating the flexible gearing appliances for driving the device for feeding the clay or other material;

Fig. 53 is a sectional detail illustrating the rollers in the frame of the device for feeding the clay or other material;

Fig. 54 is a side elevation and Fig. 55 a section illustrating the skeleton frame bearings for the press rollers and the means for providing a yielding vertical adjustment of the upper press roll;

Fig. 56 is a plan view of the means which regulates the vertical yielding adjustment device of the upper press roll;

Fig. 57 is an enlarged detail plan of one of the duplicate parts of the device illustrated in Fig. 56;

Fig. 58 is a sectional view of the same mechanism illustrated in Figs. 56 and 57;

Fig. 59 is an elevation of the face of the circumferential adjuster;

Fig. 60 is a vertical section of the circumferential adjuster;

Figs. 61, 62 and 63 are sectional details of the circumferential adjuster;

Fig. 64 illustrates a part of the profile of the upper press roll;

Fig. 65 illustrates, partly in section, the two press rolls in operation;

Fig. 66 illustrates a part of the profile of the lower press roll;

Figs. 67 and 68 are details of the pins placed in the press rolls;

Fig. 69 is a perspective view of a section of the composite metal lath made by the machine;

Fig. 70 is a perspective view of the complete machine;

That part of my machine which is a weaving machine comprises the familiar elements of a harness for alternately raising and lowering the warp wires, a shuttle which is

thrown across the machine along a race-way and through the shed formed by the opposite ranks of warp wires, and means for feeding the wires in under tension so that a quadrangular mesh may be woven. My machine, however, provides devices which at every stage not only control the operation, but which at every succession of operation must be set. My machine is automatic not merely in a sense in which that term is sometimes used but in the fuller sense of the word, in that the operating parts themselves control the machine and in which the shuttle and the wire feeding from it must be in operative condition before the machine can complete a cycle. In the operation of a machine of this character the heavy shuttle must be impelled with force across the machine and provision must be made for no possibility of its plunging out of the machine and injuring workmen. This has happened in machines in which when the shuttle is speeding across along the race-way the hold of the wire is suddenly released resulting in an acceleration or release of the shuttle with consequent danger. My machine provides that immediately upon the cessation of this retarding action by the taut wire upon the shuttle the machine shall stop. It provides also that if a wire breaks or the bobbin is emptied the machine shall instantly stop. The shuttle must also reach its outer position each time fully and properly or the machine will stop. To do this I do not provide merely that by a break some part will be brought into operation which will stop the machine, but I provide that unless these parts are properly set in each succession of operation the machine will stop. I thus always have these parts certain of operation because of their constant and positive necessity of operation. That is, they are not negative checks upon the machine, but are a part of the positive operation of the machine.

I have also provided a shuttle mechanism especially adapted to this kind of work and a shuttle-actuating mechanism also peculiarly effective. The shuttle is operated by a power independent of the power which drives the machine, but this power is provided by the action of the machine through the shuttle. The shuttle is thrown from side to side by means of a spring or springs. These springs are put under tension by the positive forcing of the shuttle outward against arms to which the operating spring is secured. At the same time the shuttle operates in connection with an automatic movable section of the race-way so that a brake is set with the result that as the shuttle moves over to the end of this positive movement the weft wire is drawn out taut. The reed, then, as it sweeps over may engage this taut wire and

pack it tightly into place between the warp wires. This operation is important because it is necessary to provide for an exact unit arrangement of the meshers of the wire fabric and to do this the weft wire must be accurately and tightly placed in this initial weaving operation.

I have provided, too, that practically all of the checking operations shall come from one shaft and that the power shall be easily and readily applied by a simple arrangement of shafting and gearing. I have provided also a mechanism which accurately and certainly takes the weft wire and measures its location and the consequent mesh of the fabric.

Furthermore, I have provided a number of details which serve to simply and accurately carry out the purpose of the weaving part of the machine.

I have especially illustrated the operative parts and their relation in Figs. 1, 2 and 4, though a number of these features also appear in relation in other figures, as in Fig. 3, for example.

In the principal figures 1 represents various parts of the frame of the machine. In Fig. 1 I have shown a broken shaft 2 driving a gear-wheel 3, the shaft leading from the press to whose operative parts extend all the setting devices hereinafter described as part of this machine. The gear-wheel 3 meshes with a gear-wheel 4 turning upon a shaft 5 journaled in a bracket on the press division. The shaft 5 operates the gear-wheel 6 turning upon a shaft 7 which extends longitudinally across the weaving part of the machine. The gear-wheel 6 serves to drive the shaft 7 through the medium of a friction disk 8, having a spring 9 secured to the shaft 7, and drives directly another gear-wheel 600 rotating a parallel shaft for purposes to be hereinafter set forth. The shaft 7 carries at the opposite end of the friction gear connection a pinion 10 which drives a gear-wheel 11, secured to and rotating a shaft 12, having its bearings in the frame of the machine. The shaft 12 carries cams 13 and 14. A stub-shaft 15 journaled in the frame and in a standard 16 carries lever-arms 17 and 18, having rollers 19 and 20 at their ends. These cams serve to alternately reciprocate the opposing parts of a harness 21 and 22, each of which receives in its heddles the warp wires. The operation is caused by the cam 13 engaging the roller 19 on the end of the lever 18 and by the operation of the cam 14 upon the roller 20 of the similar lever 17. The opposite ends of these lever-arms respectively engage turn-buckles 23 and 24, as shown in Figs. 2 and 3. As more clearly illustrated in Fig. 2 the screw-threaded ends of rods carried by the lever arms respectively engage the turn-buckles and through eyes in the top

85

130

of screw threaded rods secured in the buckles operate extending arms 25, 26 of the reciprocable harness frames 21, 22.

The chain 27 connects the ends of levers 5 17 and 18 and passes over a grooved wheel 28 which is slidingly mounted, as shown at 29, in a bracket 30.

The parts thus far described constitute the mechanism operating upon the warp wires.

10 These warp wires indicated (excepting in Figs. 7, 8 and 65) by a dot and dash or broken line, are led into the machine in the usual manner, passing over idlers 31, 32, as shown in Fig. 1. The wires run up in the 15 same plane so that in Fig. 1 but one wire appears after they have passed over the idlers 31, 32, the other wires being, as understood, behind the illustrated wire. Of two adjacent wires, one of the wires passes over 20 an idler 33, the other over an idler 34 and all the strands converge upon an idler drum 35, which is adjustably secured, as indicated at 36, to a bracket 37 on the side of the machine. The two ranks of wires having 25 passed around the drum shaft 35 diverge, one rank passing through eyes 38 in the harness 21, the other through similar eyes 39 in the harness 22. In speaking of these wires it is to be understood, as indicated, that there 30 are two series or ranks of wires constituting the warp of the fabric and that one series or rank is carried by the harness 21 and the other by the harness 22, so that when the frames of the harness are relatively reciprocated they will stretch out the two ranks 35 of wires into the customary shed or diamond figure, forming a central space through which the shuttle may be thrown. These wires, as usual, pass from the heddles of the 40 harness to the opposite side of the machine taking over a drum-shaft 40 after they have converged toward the drum. The drum-shaft 40 serves, in fact, for feeding out the completed fabric or rather the completed 45 mesh for the fabric because by that time the weft wire has been carried through the shed completing with each operation a section of the wire fabric which is then taken up over the drum-shaft 40 to be run into the adjoining 50 press to then have applied to the crossing parts the buttons of clay or similar material while under the same tension it had in the weaving.

I have provided for a rotation of the 55 drum-shaft which shall be in accordance with the operation of the other parts of the machine and especially those parts which complete the weaving. To this end on a shaft 138, to be hereinafter described, I 60 place a gear-wheel 400 (Figs. 1 and 5) by which, through the medium of an idler gear 401 held by a bracket secured to the frame, I drive a gear-wheel 402 fixed to the end of the drum-shaft 40.

In the operation of the frames 21, 22, 61 there will be a slack in the wires as they oppositely reciprocate and bring the ranks of wires nearer together throughout their length. I have provided mechanism for taking up this slack. 70

At the end of the shaft 7 (Figs. 1 and 4) is mounted a disk 41 bearing near its periphery a conical cam 42. This cam operates on a roller 43 on the end of a lever 44 pivoted at 45. As the high point of the cam 42 forces 75 backward the roller 43 an arm 46 pivoted to a bracket 47 at 48 and carrying the bracket arm 37 and with it the drum-shaft 35, is also carried outward as it is attached to the lever 44. A rod 49 transmits this motion 80 across the machine to a bell-crank lever 50, pivoted at 51. As the arm 44 moves outward it carries with it the drum shaft 35, thereby taking up the slack caused intermittently by the action of the frames 21, 22. 85 In short, the drum-shaft 35 is carried out as the wire slackens so that the wire is kept taut. I have now described the parts which operate the machine to feed in the warp wires and to reciprocate the harness which 90 carries those wires, so that the shuttle may work.

The shuttle is shown in detail in Figs. 7 and 8, in section in Fig. 7, in location in Figs. 2 and 16, 18-21, at the end of a movement in Figs. 1 and 3, and in transit in Fig. 4.

The shuttle 52 travels upon a frame 53, shown in the illustration as substantially of inverted U-shape, secured to a bracket 54 100 and having an inclined top, as shown in Figs. 1, 2, 7 and 16, as well as in the details, Figs. 18-21. On the opposite sides of the frame 53 and at the top are placed flanged plates 55, 56, secured to the frame 53, as 105 shown in Figs. 1, 4 and 6.

As shown especially in Figs. 4 and 6, the plates 55 and 56 have recesses 57 cut from the top inward for the purpose of receiving the weft wires so that they may pass under 110 the shuttle, as indicated in the various figures noted and as especially shown in Fig. 7 and in the details Figs. 18-21. This shuttle, as illustrated in detail in Figs. 7 and 8, comprises a bobbin spool 58 which rotates upon 115 a shaft 59 secured to the bottom of the shuttle. This spool carries, as shown, the weft wire and it has adjunctive braking mechanisms and devices for tightening the wire to be hereinafter described. The shuttle is 120 driven to and fro upon the inclined frame 53, guided by grooves 60 in the bottom fitting over the flanged plates 55, 56. The driving power is imparted by a spring 61 (Figs. 4 and 6). The spring 61 is held at 125 opposite ends by hooks 62 and 63. I have shown one spring, but, obviously, a multiple spring may be used. 64 and 65 are swinging

forked bars pivoted to upright bars 66, 67, as shown especially in Figs. 6, 2 and 3. The hooks 62 and 63 have upon their screw-threaded ends nuts 68, 69 from which project 5 pins 70, 71. These pins take into recesses in blocks 72 and 73 which are integral with or secured to plates 74 and 75, bolted, as indicated, to narrow plates 76, 77 on the opposite side, so that the blocks 72 and 73 are 10 clamped to the swinging frames 64 and 65. By this means the parts are readily adjustable. Near the bottom of the frame 64 there is shown an impact projection 78. A similar part is on the frame 65 but is hidden from 15 view by other features in Fig. 6 and in Fig. 3. There is also secured to the bottom of the arm 64 a screw-threaded bolt 79, which serves as a stop to determine the amount of inward travel the arm 64 shall have.

20 It is intended that a cam 80 on the shaft 81 or a similar cam on a shaft 810 when the shuttle reaches the end of a stroke, shall sweep across the back of the shuttle and push it out against the projecting part 78 so as to 25 put the spring 61 under tension in an obvious manner. When the shuttle is drawn across the race-way under ordinary circumstances it might find its place too abruptly, and I have therefore provided buffer devices which in any event would prevent too 30 great a shock at either end. These buffers consist of weights 82 borne by pivoted depending arms 83. The weights are illustrated in place in Fig. 6 and in detail in 35 Figs. 12-15. They are in different horizontal planes because the shuttle is inclined.

The weights 82 on one side are carried by the depending swinging arms 83 and the weights on the other side by two similar 40 swinging arms. Both sides have buffers 84. These buffers are of raw hide or rubber or some similar material fitting in sockets 85, the inner ends of which show in dotted lines in Fig. 14.

45 86 is a buffer in the end of an adjusting rod 87, which passes through spacing blocks 88, 89 between the weights. The buffer 86 prevents the weights from bringing metal against metal in case of a rebound after the shuttle has driven back the weights. The adjustment by the adjusting rod is to regulate the placing of the outer end of the buffers. The weights are bound by bolts 91, threaded at the outer end to receive nuts as 50 shown, and the adjusting rod is held in place by a set-screw 90.

When the shuttle first strikes the buffers the arms 83 are swung back but this does not affect the action of the arms 64, 65. The 55 shuttle pushes back these arms by operating against the projection 78 whose inner end is rounded so that as the shuttle swings on the arm 64, for example, it will keep in constant contact with the curved surface of the pro-

jection, which when a catch, to be described, 65 is released will impel the shuttle in the opposite direction under the impulse imparted by the release of the tense spring 61.

It is also obviously necessary to provide 70 a device for catching and temporarily holding the shuttle at each end. The devices for this purpose are illustrated in Figs. 3, 4, 6 and 11. They are detailed in Fig. 11 and shown located in Figs. 3, 4 and 6. In Fig. 4 they are lettered on one side only to prevent 75 confusion of the drawing on the other side. The shuttle is shown with catches 92 which are to alternately engage a pivoted latch 93 at each end of the machine. This latch is connected by a pivoted, slotted arm 94 to a 80 pivoted, inclined lever-arm 95 having a spring connection at 96 with the bracket bearing in which is journaled the shaft 810, these parts being duplicated at the other end about the shaft 81. The slot in the link 94 85 allows the upwardly spring pressed lever 93 to be depressed when engaged by the catch 92 on the shuttle without affecting the position of the arm 95.

In describing the driving gear mechanism 90 of the machine I have before referred to the fact that the gear-wheel 6 itself directly drives a gear-wheel which rotates a transverse shaft and I have also referred to this shaft 81 as the shaft which carries the cam 95 80 for sweeping forward the shuttle intermittently, and I have also described the shaft 810 and the duplicate parts on the other side. The gear-wheel which rotates the shaft 81, for example, is numbered 600 100 and is shown, for example, in Figs. 1, 2 and 4, and incidentally elsewhere. A shaft 98 runs across the machine and, as before stated, carries most of the cams, etc., for effecting the checking operations of the machine. On the shaft 98 at each end is a helical gear 97. One of the helical gears, that to the right of Fig. 4, is driven by a helical gear 99 which is carried by the shaft 81. The rotating movement is carried 105 through the shaft 98 and imparted at the opposite end to a helical gear 99 which serves to rotate the shaft 810 and thus to operate the cam 80 at that end as well as to perform another operation now to be described.

I have described these features at this 110 point because they lead directly to a description of the mechanism at each end of the machine for releasing the shuttle after it is latched.

The shaft 810 carries and rotates a pinion 100 (Fig. 11) and this pinion rotates a gear-wheel 101, turning upon a stub-shaft 102 secured to the bracket named. On the wheel 101 is a cam 103. As the wheel 101 rotates 115 the cam 103 will wipe the lever 95 depressing it at intervals, the spring 96 returning it. As the cam 80 pushes forward the shuttle 120 52

- the catch 92 is removed from the latch 93. It is necessary to move the latch 93 out of the path of the shuttle and this is done by the action of the cam 103 upon the lever arm 95. It will be understood that there is a set of these parts for locking and releasing the shuttle at each end of the machine, one set, as described, being associated with the shaft 81, the other set with the shaft 810.
- 10 The arm 95, shown in detail in Fig. 11, is a curved arm and this curvature appears in other figures of the drawings, notably in Fig. 4, in which the parts are shown on both sides operated by the described helical gears 97, 99 and the shaft 98.
- 15 In the action of the shuttle it is essential to provide for tightening the wire and controlling the operation of the spool. Returning now to Figs. 7-10. At 104 is shown an annular brake. Above this is another annulus 105. The brake part, in the illustrated form, consists of a cup-shaped body 106, one at each end of a shaft. The brake is operated from a cam 107 on shaft 98 (Fig. 16) which operates lever 108 pivoted at 109 and engages at the outer end a screw-threaded rod 110 with a forked end which operates a connecting arm 111 whose function is to raise a bar 112 as a roller 113 pivoted upon the shuttle strikes it. The bar is carried by a pivoted arm 114 having a spring 115. The effect of this is to raise a shaft 116 and thereby depress a spring plate 117 pivoted at 118. This has the effect of pressing the annular brake 104 through the ring 105 against the spool so that it will act as a brake.
- 20 I have provided for regulating this tightening device or retarding device. A set-screw 119 operating on the plate below it governs the tension. I also have a set-screw 120 by which I get a more limited braking adjustment so as to keep the wire taut while the shuttle is crossing the machine.
- 25 The pivot block 116 has projecting rods 121, 122 which are journaled in boxes 123 and held down by clips 124, as hereinafter described. The pivot block 118 has also an extending stub through which passes the set-screw 120. The pivot block 118 carries the
- 30 spring extension 117 which presses upon a plate 125 secured at one end by a threaded sleeve 126 through which passes the set-screw 120 and at the other end is secured to the cup 106. The screw 120 also has some effect on the position of the wheel or roller 113 and also thus affects that braking. As 35 120 is turned to take its end away from the body of the shuttle it would release the pressure on 116, changing the fulcrum point 118.
- 35 40 There is a constant braking action governed by 120, for it governs the position of the wheel 113 and thereby controls the action at the end. I have provided for the ready removal of the brake parts so that the bobbin

may be quickly reached or removed. The 65 shafts 121, 122 are journaled in the box 123 open at the top and each having a spring-drawn securing clip 124, hinged at the bottom so that it may be turned over to free the ends of the shafts and then upon the return 70 of the shafts spring back into place.

It is necessary to guide the weft wire out of the shuttle with great care. The wires pass out through an opening or slot 127 and cross a roller 128, thence around rollers 129 75 or 130 depending upon the position of the shuttle in the race-way. These two rollers 129 and 130 are journaled in a spring-pressed frame 131. The springs 132, appearing on each side of the frame, abut against perforated lugs 133 which surround a shaft 134 integral with a frame 135. The effect of this is to permit a yielding of one of the rollers as the wire is drawn out of the slot across the roller rod 128 and around the roller 129 85 or 130. When the shuttle is first struck to throw it over, the spool would not feed as rapidly as the shuttle is moved and there would therefore be a great strain on the wire. This strain is taken up by the rollers 129, 90 130.

The shuttle thus controlled and governed by the described parts and operated by the spring 61 has always the same speed when it is thrown across the machine. This is an 95 important factor, for in any weaving machines where there is a rapid operation the shuttle is driven at a dangerous speed. In my machine the shuttle may be more or less frequently reciprocated but no matter how 100 often it may be reciprocated it is always thrown at the same speed. The cam 80 may push the shuttle in a rapid succession of operations but cannot push it farther or give more effect to the spring 61 in any instance 105 though the spring may operate oftener in a given time.

I have also provided a device by which the operation of the machine is governed through the motion of the shuttle as it nears the end 110 of its movement. Inasmuch, however, as this is intimately involved with the automatic features of the machine the description will be postponed.

The shuttle as it passes along the race-way feeds out first to one side and then to the other, as illustrated and indicated in Figs. 4 and 8, the weft wire which is to be applied and tightened.

(Figs. 1, 2, 3, 4, 18-21.) On the shaft 7 120 is mounted a helical gear 136 which engages a helical gear 137 on a shaft 138, rotating the shaft, which has its bearings in the side frames. Near the opposite ends of the shaft 138 are toothed wheels 139 and 140. It is 125 the function of these wheels to engage and hold the weft wire, and the teeth are separated from each other in accordance with the

desired width of the mesh of fabric and are formed to first hold the wires and then release them readily.

At 141 and 143 is pivoted a reed or comb 5 142 which is to take the weft wire fed from the shuttle and carry it over and put it alternately about a tooth of the wheels 139, 140. In this operation it is desired to oscillate the reed 142 and also to first raise the reed to 10 engage the wire, and then again raise the reed slightly after it first engages the wire to prevent it from slipping off, and then move it over so that the wire may be carried forward, as shown in Figs. 18-24, and placed 15 over the teeth of a wheel 139 or 140.

The reed is primarily pivoted on a shaft 143 and a cam 144 on the shaft 98 raises a 20 lever 145 pivoted in an arm or bracket 146 depending from the under side of the frame 53, and with it the shaft 143, turning them about the pivot 141 so that the reed 142 is raised to a place back of the bobbin wire. A cam 147 also on the shaft 98 now moves the reed forward and takes with it the weft wire 25 and places the wire about one of the teeth of the wheel 139. Directly after this operation the cam 144 runs off of the lever 145 and allows it to drop, at the same time lowering the shaft 143 and moving the reed down- 30 wardly. The forward movement of the reed is due to the wiping of the cams 147 upon rollers 149 borne by stub-shafts in each arm of the reed. A spring 148 pulls back the reed 142 as soon as the cams 147 have cleared 35 the rollers 149.

The reed is shown with a toothed part carried by the arms which operate the shuttle wire. These teeth are to permit the warp wires to lie between them so that when the 40 reed sweeps over it will pass through these wires while the outside arms 1420 of the reeds will engage the weft wire of the shuttle and carry it over to be secured on one of the saw-toothed wheels 139 or 140. It will be 45 observed that the shuttle-wire lies diagonally across the machine so that at each reciprocation one of the arms 1420, lying outside the toothed part of the reed, will first engage the wire (Figs. 3, 4 and 17).

50 In Figs. 22 and 23 I have illustrated the form of tooth which I find effective in handling the wires. It will be observed that they are lower in front than at the rear and that they have an arc-shaped top. This 55 form of tooth provides for securely holding the wire placed about it while at the same time permitting ready discharge from the tooth as the wheel moves around in the direction of the arrow.

60 In Figs. 24 and 25 I have illustrated the manner in which the wires take about the tooth and the way in which they cross each other and, in accordance with the principles of weaving, provide for forming a selvage.

I have heretofore referred to the co-action 65 between the positive movement of the shuttle after its spring throw by which when the brake is applied the weft wire is tightened. It is immediately after this tightening effect 70 that the reed comes into operation so as to take this tightly drawn wire and pack it into place between the warp wires.

I have referred to the automatic checking devices by which I am enabled to have the machine set for each operation and by which 75 I provide that the shuttle must each time complete its throw across the machine and by which I provide that there must always be a taut wire in place and running from the shuttle. 80

I will now describe the automatic checking operations which are controlled by the action of the shuttle and by the movement of the wire as it is fed from the shuttle. These parts are illustrated generally in Figs. 1, 2 85 and 4, and in detail in Figs. 26-31.

The shaft 7 bears two cams 150 and 151. These cams bear respectively upon rollers in the end of the upper arms of levers 152 and 153. The levers are bent and, as indicated, 90 have a lower and upper part, each of the levers as a whole turning on a pivot held in a bracket secured, as indicated, to the frame of the machine. At the lower end the levers 152 and 153 have respectively pins 154, 155, 95 which rest, one in a box 156, the other in a box 157, secured to slide-bars 158, 159. On the outer end of the bars 158 and 159 is secured respectively a cylindrical bearing 160 and 161. Rods 162 and 163 pass through 100 these cylindrical bearings and normally project through them as shown in Figs. 1 and 3, being indicated as withdrawn in Figs. 26 and 29 at the points 164, 165. They have enlarged heads 166 with split threaded parts 105 167 for each arm, and each bears a spring to insure the return of the corresponding rod.

At each end of the machine is a roller 168 held at an inclination in accordance with 110 the inclination of the shuttle and so that the side of the shuttle may strike the roller as the shuttle nears the end of its travel as illustrated, for example, in Figs. 1, 4 and 27. The roller 168 is carried by an arm 115 which is pivoted to a bracket 169 attached to the main frame. The roller 168 operates a short shaft 170 attached to an arm 171 which in turn is secured to a short shaft or pin 172 on a connecting link 173 which 120 operates an arm 174 secured to and operating a shaft 175 which through a rod 176 lifts the flexible extension 167 and through it controls the operation of the slide-bar 158.

In the ordinary operation of the machine 125 the mechanism would stop soon after starting because as the shaft 7 turns and brings into operation the cams 150, 151 the effect

would be to throw forward, as illustrated, the slide-bar 158. Then the rods 163 projecting from the bottom of the bar 158 would engage the operating rod 179 throwing it forward, releasing the clutch of the driving mechanism on the press part of the machine and thus stopping the machine, but by the mechanism just described when the shuttle is properly operating it will actuate the 10 roller 168, and, through the connected parts, will draw up either the rod 162 or the rod 163 so that there will be nothing to contact with the slide bar 158 and it will, therefore, not be slid forward to engage with the operating rod 179.

The same kind of operation is illustrated in Figs. 29-31. In that case a shaft 177 has secured to it, one at each side of the machine, upwardly extending bars 178 which 20 lie in the path of the weft wire, as illustrated in Figs. 29, 1, 3 and 2. When the wire is stretched across by the shuttle and then brought over by the action of the reed 142 the wire will strike one of the arms 178 as the wire lies diagonally across the machine and will turn the shaft 177 operating the 25 flexible extensions, 167, the rod 164 and the slide-bar 159. It will be understood that when this operation takes place and the rod 30 164 is drawn up the slide-bar 159 will move over the bar 179 without effect and the machine will continue its operation. However, if for any reason the wire does not strike the arm 178 then the rod 164 will remain in the 35 position as illustrated in Figs. 1 and 3, projecting, and will carry over the bar 179 throwing the clutch out of engagement and stopping the machine. As will be herein-after described, the machine stops instantly 40 through the operation of a brake which acts synchronously with the release of the clutch.

The bar 179 at the beginning runs transversely across the machine but, obviously, to reach the connection with the other part of 45 the machine must turn at right angles. The provisions for accomplishing this are illustrated specifically in Fig. 37^a where a bell crank lever 1790 transmits the motion from the bar 179 to a rod 1791 which, through a 50 drop lever 1792 operates the rod 217 running to the clutch mechanism.

I will now describe the structure and operation of that part of my machine which I briefly term the press.

55 It will be seen that the driving and braking mechanism of the parts 200-232 inclusive are applicable to the weaving machine part whether used with the described press mechanisms, or some other mechanism, or 60 alone.

The wire fabric with the quadrangular mesh comes tightly woven and under tension directly from the weaving part of the machine to the press, entering and passing 65 through the machine substantially as indi-

cated by the broken or dot and dash line in Fig. 1.

The fabric is engaged and drawn into the machine by a feed roller having a profile with pyramidal sections separated by beveled grooves so that the sections may fit in the interstices of the wire fabric to firmly engage and feed it forward to the lower press roll. Hooks upon the lower press roll engage the wires at the junction point and 70 draw the fabric between the two press rolls. Here it meets a stream of clay strips or other material fed in between the press rolls, the press rolls having patterned profiles to properly engage and pattern the upper and lower 75 surfaces of the clay coating. The effect of the sectional projections on the profiles of the press rollers is to not only produce a grooved or scored surface but also to force aside the clay between two opposite buttons 80 so as to weaken the line, say circumferentially, to make the fabric more flexible. It will be obvious if the wire fabric kept its complete coating on both sides it would be impracticable to handle after having been 85 baked and it must, therefore, be made more flexible. As indicated, the operation of the press rolls partially accomplishes this but I complete it by passing the wire fabric between two rolls having opposed conical cutting rings and by following this by passing 90 the material between a set of supporting rollers and a punching roll having on its surface projections adapted to pass through the interstices of the coated fabric and force 95 out superfluous material, leaving an article having the wire fabric embedded in the plastic material and having at each conjunction of the wires a corrugated or indented clay or other button with the part between 100 two buttons so cut away as to nearly bare the wire and thus render the fabric flexible 105 and easily applied.

The wire fabric with its coating of buttons constitutes the finished product so far as 110 this machine is concerned as it is received upon the winding reel at the rear of the machine ready to be baked in another apparatus. To keep the clay or similar material in proper condition for the action of the 115 parts which give the conformation to the fabric I find it necessary to heat the press rolls and other parts which treat the composite fabric as it passes through the press and to this end I have specially provided devices for this purpose and for the different gradations required. I have also provided a device for feeding in the clay and strips and for controlling and guiding the operation of the clay feeding mechanism. In 120 running through the wire fabric and the clay coating I find it necessary to provide various adjustments for the press rolls. I have circumferential adjustments to bring the profiles of the press into exact register with each 125 130

other, means for adjusting the distances between the presses, means for permitting the rollers to yield in case any hard, foreign substance should pass between them and means for adjusting the bearings of the presses to properly locate them in the frame of the machine and to give also the proper transverse adjustment to the profiles of the two press rolls.

10 I have also provided devices for starting the winding reel, means for oiling the surfaces of the press rolls and other parts, and details of mechanism for completing the necessary operation of the press.

15 I have hereinbefore pointed out the unitary arrangement of the parts. That is, how the wire fabric is woven with relation to the essential accuracy of the press part of the machine. As the wire fabric comes over 20 the feed roller 40 to the feeding roller 240 the distance from the top center of the feed roller 40 to the place where the fabric is taken by the feeding roller 240 is a multiple 25 of the units of the fabric. The feeding roller accurately places the wires to form the mesh, and this mesh precisely fits upon and is held firmly between the press rolls so that the clay buttons shall be found precisely placed over the intersections of the wires.

30 As has been before stated the power mechanism of the press operates also the weaving part of the machine and the throw-out devices of the press are automatically operated by the weaving part of the machine. These power devices are especially 35 illustrated in Figs. 32, 35 and 36 and the relation of the gearing to the press rolls in Fig. 40.

The press is driven by a belt which rotates 40 a pulley 200 upon a stub-shaft 201. The stub-shaft 201 is bolted to a bracket 202 and secured by a nut 203. (See Figs. 35 and 37.) The bracket 202 is an extension of a bearing 204 which together with bearings 205 and 45 206, as shown in Fig. 32, constitutes three supports for worm-shaft 207. The pulley 200 carries within it an expanding clutch 208 operated by a series of levers hereinafter described. A beveled gear-wheel 209 is formed 50 integral with the clutch so that when the clutch engages the pulley 200 the beveled gear-wheel 209 will be rotated. The beveled gear-wheel 209 engages a beveled gear-wheel 210 which is keyed to the counter-shaft 207.

55 On the opposite end of the shaft 207 is mounted the pinion 3 and this pinion drives the intermediate gear-wheel 4 on the shaft 5 which transmits power to the weaving machinery. The intermediate gear-wheel or 60 idler 4 mounted on the shaft 5, rests at one end in a bearing 211 on the frame of the press part of the machine, and at the other end in the frame 1 of the weaving machine where it is secured by a nut 212.

65 The expanding clutch 208 (see Figs. 37-39)

is governed and operated by hand levers 213 and 214, one on each side of the machine. The expanding clutch is also controlled and operated from the wire weaving part of the machine by means of a rod or bar 179, before 70 described, which comes from the wire weaving part of the machine and operates if there should be a break in the wire or the shuttle should not reach its maximum end position. As before described, either of these 75 failures would result in the automatic stopping of both the weaving part of the machine and the press part of the machine. The hand levers 213 and 214 have downwardly extending arms 215 to the lower ends of 80 which are pivoted curved links 216. A shaft 217 forms a support for the hand levers 213 and 214 and this shaft extends across the machine. The curved link 216 is connected at one end to a bell-crank lever 218. The 85 bell-crank lever is pivoted at 219 to a suitable support 220 which extends from the side frame of the machine. To the other end of the bell-crank lever 218 is secured a link 221 which is fastened to a lever 222 pivoted 90 to the frame of the machine at 223. The lever 222 engages a collar 224 at the point 225. The collar 224 operates a cone surface 226 which may be forced against spring 95 pressed pins 227 which are connected to arms 228 pivoted in turn to the expanding clutch ring. The clutch rings, as is customary, are pivoted at 229 within the pulley and are relatively spring-drawn by springs 230. Obviously when the cone is pressed against the 100 pins the clutch rings will be forced against the inner surface of the pulley by the operation of the levers.

In this connection I have also provided a braking mechanism. A brake-shoe 231 clears 105 the outer rim of the friction clutch. When the clutch is thrown out by the movement of the lever 222 toward the center of the machine through the operation of the hand levers 213 or 214 or the rod 179 the conical 110 operating part 226 is withdrawn from the clutch releasing it and at the same time the brake-shoe 231 is forced against the rim of the clutch and quickly stops the movement 115 of the machine. The brake-shoe may be applied in various ways but I have shown it as bolted to studs 232 which are in turn bolted to the lever arm 222.

The press-rolls and their attendant parts are driven from the shaft 207. On this shaft 120 is a worm 233 which engages and drives a worm gear 234 mounted on a cross-shaft 235 extending across the machine and having bearing in two standards 236 and 237, and having a bearing also in a bracket 238 bolted 125 to a standard 239. (Figs. 32 and 36). The cross-shaft 235 carries and rotates a feeding roller 240 around which the wire fabric passes in entering the press and which preserves the fixed relation of the fabric as it 130

passes into the press rolls. This roller, as indicated in Fig. 46, has pyramidal projections similar to those on the press-rolls to be hereinafter described, which take into the 5 interstices of the wire thus placing and feeding it at once.

The small ends or apexes of these pyramidal projections take into the mesh of the fabric accurately adjusted as to the relation 10 between the weft wires and the warp wires but not yet accurately adjusted as to the distance apart of the warp wires. As the fabric is drawn about the feeding roller the wires slip down to the base of the projections 15 and there are given the unit form of the fabric to fit the unit form of the press rolls to which the wire fabric now goes.

The two press rolls 241 and 242 are journaled, as will be further shown, in the standards 236, 237. Keyed to the shaft 235 is a pinion 243 which meshes with a large gear-wheel 244 keyed to one of two stub-shafts 245 which carry the lower press roll, and which in the form here shown are integral 25 with the heads of the rolls. A second gear-wheel 246 is also secured to one of the stub-shafts 245 beside the large gear-wheel 244, and meshes with a gear-wheel 247 keyed to one of two stub-shafts 248 which carry the 30 upper press roll, either integral with or secured to its head. This is the mechanism which serves to rotate the press-rolls and carry through the wire fabric and its coating of clay.

35 On the opposite side of the machine are a set of gears which receive power through the cross-shaft 235 and communicate the power to gear-wheels which rotate the cutting and cleaning or punching rollers to be described.

40 On this side of the machine is a gear-wheel 249 fixed upon the shaft 235 and engaging an idler or intermediate gear-wheel 250 which in turn drives a plurality of idlers or intermediate gear-wheels 251, 252, 253 and

45 254. The gear-wheel 253 operates a gear-wheel 255 which is keyed to a shaft carrying a cutting or scoring roll 257. Immediately opposite and working with this cutting roll is another cutting roll 256, which may be driven by a gear connection operated from the shaft which carries the roller 257, as indicated in Fig. 35 and Fig. 70 and not necessary to more fully illustrate so that the fabric with the clay lining will pass between 50 these cutting-rolls as illustrated, for example, in Fig. 41. The purpose of these knife cutting-rolls is to cut circumferential grooves in the coating of the fabric to make it more flexible.

60 The fabric as it comes out from the press rolls is patterned in such manner as to be flexible at the intersection of the joints and the intersection of the wires running in one direction, but there remains along circumferential lines of the fabric pyramidal projec-

tions of clay. The cutters of the rolls described run through the center of these pyramidal projections so that throughout the length of the fabric and along the intersecting lines runs a clearly defined groove on 70 each side formed by the operation of the cutting rollers.

The gear-wheel 254 engages a gear-wheel 258 which is keyed to a cross-shaft bearing a cleaning roller 259, (Figs. 32, 35, 36, 42 75 and 70) carrying a series of teeth as indicated at 260, whose function is to stamp out the surplus material in the open squares of the fabric. Beneath the cleaning roll are located two idler rolls 261 and 262 to hold 80 the material while the toothed wheels perform their function of cleaning out the surplus material.

Integral with the gear-wheel or idler 254 is another idler 263 mounted on the same 85 stub as the gear-wheel 254. This idler 263 engages another idler 264 which in turn rotates a gear-wheel 265. The gear-wheel 265 is attached to the sleeve of a friction disk 266 which operates a winding up reel 267 90 extending across the rear of the machine. This reel is shown in Figs. 32 and 70 and in detail broken away in Fig. 35 at the bottom, while its operating parts, now to be described, are shown in detail in Fig. 43. 95

Into a conical cup or recess 268 in the end of this reel passes a similar hub 269 preferably webbed so as to fit closely into corresponding grooves in the walls of a cup in the ends of the roll. The conical cup extends 100 from a part of a shaft 270 extending outward and bearing at the end locking nuts 271 beneath which lies a spring device 272 with the usual collars surrounding the threaded head of the shaft. This shaft 105 passes through a hub 273 of a friction clutch member which has bearings in brackets 274 on the frame. This hub has keyed to it the gear-wheel 265 which is driven by one of a train of gears previously described. 110 Lying between the bracket in which the shaft is journaled and the face of the friction clutch member described is an opposite friction clutch member 275 which in this case takes the form of a hand wheel for purposes to be described. 115

In the ordinary operation the fabric reel will be operated through the medium of the friction clutch and the cone head engagement. It is necessary to make some provision 120 for starting the winding. A slot 2670 is formed in the hollow reel extending through the reel and nearly to the opposite end. In the operation of the machine the fabric with the clay buttons is fed through far enough 125 to reach the point where it will lie slightly beyond the reel. The reel is then removed from its bearings and the open slotted end is pushed in across the fabric, the lips of the slot passing along the depressions in the 130

fabric. When the reel has taken in the width of the fabric the buttons then lying within the reel cannot be drawn out and they form a head by which the fabric may be gripped in the slot. Then when the reel is put in place the nuts at the head of the shaft may be loosened, taking off the spring pressure against the hub of the friction clutch of the spring member so that the 10 grips of the hand wheel may be grasped to rotate the reel and wind the fabric about the body of the reel. It is understood, of course, that the machine is stopped during this operation. Then upon the operation of 15 the machine the fabric will be wound about the reel by the now tightened friction clutch.

While I do not dwell upon this refinement it will be obvious that it will be advisable to slightly taper the reel so that it 20 may the more easily be drawn out of the enveloping roll of material.

The heating apparatus for the rolls is illustrated in detail in Figs. 44 and 45 and is shown in location and section in Figs. 35 25 and 40. It is also incidentally shown in Fig. 36. The heating device of Fig. 44 is upon a familiar principle with, however, the further provision that the press-roll may be rotated while permitting the introduction of the steam or other heating medium and providing at the same time a safety-valve. In Fig. 44 at the right-hand side in section is shown a stub-shaft which carries a press-roll. At the outer end of this 30 35 stub-shaft is a cup 277 screw-threaded into the head of the stub-shaft and centrally channeled or perforated. Lying in this cup is another bearing cup 278 similarly perforated or channeled against which lies the nozzle 279 of the heating member. This heating member or nozzle has a round head which fits into the bearing cup 278 described, so that the bearing cup may rotate against the fixed head of the steam member or nozzle. This steam member or nozzle has a channel 280 coinciding with the channels previously described and has also, as illustrated, inlet and outlet channels to be described. Through the mouth of the steam nozzle 50 passes an outlet pipe 281 which leads into the press-roll as shown especially in Fig. 40. This is screw-threaded into the steam nozzle and the steam nozzle has a channel 282 corresponding with the channel of the outlet 55 pipe and leading, as usual, into an enlarged channel 283 at the outer end of the steam nozzle which then communicates with a swivel pipe connection 284 held in the usual way by a cap 285 and communicating with a flexible or other pipe 286 which leads off the exhaust steam. The inlet is provided, as indicated, by similar connection pipe communication, swiveled head or cap and a right-angle channel member 287 so that the 60 65 steam may pass through the nozzle around the outlet pipe and thence out of the outlet pipe, as described. To securely hold these nozzles as they project from the press-rolls I have provided an upright plate 288 through which the nozzles pass, the plate being held by a pair of arms 289 as indicated, especially in Fig. 40. Between the plate and the shoulder on the nozzle lies a spring 290 which keeps the head of the nozzle pressed against its bearing cup so as to maintain constant and uniform contact, and yet provide a connection which may yield under undue pressure of steam to act as a safety-valve. It will be observed that I have in this case an independent supply of steam 70 75 for each of the press-rolls. In heating the knife and other rolls which are much smaller, it is not necessary that I should have an independent supply for each of the rolls, I have, therefore, a device which economizes 80 85 the distribution of steam so that the same flow of steam will heat each of the rolls. This is illustrated in Figs. 35 and 45, the illustration of Fig. 45 being both perspective and diagrammatic. In this structure 90 the steam enters a nozzle 291 similar to the nozzle previously described. The steam then passes into the lower knife-roll 256. The steam then goes out by the dotted line pipe 292 into the goose neck pipe 293, around 95 into the cleaning roll 262, then out from that into a goose neck 294 on the other side, thence through the nozzle into the dotted line pipe 295 discharging into the upper knife-roll 257, and then exhausts out of that into 100 a nozzle 296 which is described in the preceding description. The nozzles of this connection are similarly pressed through a spring 297 which in this case is shown in the center of the goose neck. The goose neck 105 in the detail is shown projecting upward, but in the general view, Fig. 35 is shown pointing down. It is immaterial in which way it is arranged.

The mechanism for feeding the clay or other material is illustrated in Figs. 32, 35, 46 to 53 and incidentally elsewhere. A series of rollers 298 are journaled in a hinged frame 299 which is carried by a bracket 300 or, rather, indirectly supported on the 110 bracket by a pivoted arm 301. The hinge of the frame is indicated at 302 Fig. 46. At the bottom of the frame is a projecting guide-piece 303, one on each side, its construction and adjustable application being 115 illustrated in Figs. 48-50. This forms a guide to prevent any clay from being forced out to the side as it enters between the press-rolls. Alternate rollers of the clay-feeding 120 device bear at one end gear-wheels 304 and between each two of the gear-wheels is an idler 305 so that these alternate rolls are rotated. Between each of these rotated rolls is a roll 306 which may be turned in the bearings in the frame by the action of the 125 130

clay passing over the sets of rolls which are all in the same plane. The rolls which bear the gear-wheels also carry division disks 307 as shown, for example, in detail in Fig. 53, so that strips of clay may be fed in, each strip lying between two opposed disks. All the rolls may be made in sections as indicated, separating disks dividing the sections of one set of rolls. The fact that these rolls are made in separate sections permits a better feeding of the strips because then each strip may travel independently of another.

In view of the fact that the clay feeding device is adjustable it is necessary to have some form of adjustable or flexible gearing which may yield with the adjustment of the clay feeding device and yet maintain an operative driving relation.

The device for driving the clay feeding rolls is illustrated in Figs. 32, 51, 52 and 70, the illustration in the latter figure being of a slight modification involving, however, so much of the same principle that substantially the same description and the same reference letters will answer for both forms. There are two driving chains. A pinion 308 on the shaft 235 drives the sprocket chain 309 and passes over two central pinions 310, 311, both of which are carried by a bracket 312. A shaft 313 which carries the pinion 310 has at the opposite end a pinion 314. The shaft 310 passes, as illustrated in Fig. 52, through a bushing and upon this bushing are journaled two arms 315, 316 adjustably secured thereto and bearing respectively pinions 314, 318. The pinions 311, 318 are in reality idler pinions for the power is transmitted to the pinion 314 and thence to a pinion 319, the upper chain being spread apart by the pinions 314, 318 in the same manner in which the lower chain is spread apart in the center. It will be obvious that the idler pinions may be adjusted up or down to accord with a similar movement of the clay feeding device and to permit the sprocket chains to accommodate themselves to be either lengthened or shortened, as the case may be.

Substantially the same idea is carried out in Fig. 70 excepting that the central pinions are not there illustrated as in substantially the same line.

I will now describe the various means for adjusting the press-rolls there being four means for securing the full adjustment. In the ordinary running of the press it would be sufficient to set the press-rolls but I have provided also mechanism by which I may vertically adjust the upper press roll or permit the upper press-roll to adjust itself if any foreign substance should pass between the press rolls. I, therefore, prevent damage to either the product or the press-rolls in such an event.

The press-rolls, as heretofore described,

have stub-shafts preferably integral with the circular heads of the hollow press-rolls. These stub-shafts, as described, are journaled in the frame of the machine and the position of their journals and of the vertical adjusting device is illustrated in Figs. 32, 35, 36, 40, 54 to 58.

The frames of the machine are especially adapted to provisions for regulating the adjustments of the bearings of the press-rolls. They are in skeleton form and in separable sections as illustrated, for example, in Figs. 32, 54 and 55, where screw-threaded bolts 320 are shown securing one of the parts of the frame to the other parts. One part of the frame is roughly U-shaped with a hollow wall, while the other part is substantially a straight hollow member fitting up against the solid projecting arms of the opposite member and secured thereto as before described. The frames are alined and braced by tie-rods 321 screw-threaded at each end and having intermediate turn-buckles 322.

Between the parts of the frames there is an intermediate space. The bottom of this space is occupied by the journal bearing 325 and the bushing 323 for the lower press-roll, while some distance above is supported the bushing 324 and the journal block 326 for the upper press-roll. Between these bushings and the journal blocks lies a hollow spacing member 327 which rests upon the journal block 325. Between the journal block 326 and the spacing member 327 is a wedge 328. In the illustration of Fig. 55 I have shown a projecting reduced head on the spacing member 327 which forms a base for the wedge 328. But in Fig. 40, where the wedge shape is more clearly shown, I have indicated a separate block resting on the spacing member 327 and providing an inclined path for the wedge. 330 represents a screw for operating the wedge. By turning the screw 330 the wedge may be moved inwardly or outwardly as the case may be and the bearings of the upper press-roll may be accordingly elevated or lowered. The same device is applied on each side of the machine and of course the same adjustment may be made on each side. This adjustment is of a kind which provides for practical precision because the position of the wedge or the relative position of the screw is easily ascertained so that both sides may be equally adjusted.

I have provided further for a duplicated vertical adjustment which is also a yielding adjustment. On each side there is a hollow screw-threaded bolt 331 threaded within the side frame. Keyed to the hollow bolt 331 is a ratchet wheel 332. Each ratchet wheel has an upper hub 333 and a lower hub 334. Journaled about or turning upon each of these hubs is an upper plate 335 and a lower plate with extending arms forming a lever 130

member 336. 337 and 338 represent pawls which engage the ratchet wheel 332. These pawls operate upon the principle of a bell-crank lever and are normally held in engagement with the teeth of the ratchet wheels by a spring 339. The inner arms of these bell-crank levers are provided with extensions or dogs 340. These dogs are operated by cam surfaces of a cam 341 which is pivotally mounted upon the lever member 336. Each cam has an arm 342 and the arms of the two cams are connected across the machine by a bar or rod 343. It is apparent that any movement of the rod or bar 343 will effect the simultaneous but opposite movement of the cams 341 and this movement is illustrated, for example, in Fig. 56. As there illustrated the bell-crank pawls are in their neutral positions with respect to the ratchet wheel 332. In order to effect an elevation or a lowering of the hollow screw-bolt 331 the rod 343 is moved to the position shown in dotted lines in Figs. 56 and 57. Such a movement of this rod turns the respective cams 341 upon their pivots and causes a cam surface of the cam 341 to engage one of the extensions or dogs 340 of the bell-crank pawl. In this position it will be seen that two of the bell-crank pawls, that is, one on each side of the machine, will be rendered inoperative with respect to the ratchet wheels. Likewise a reverse movement of the rod 343 will effect the dis-engagement of the opposite set of bell-crank pawls. It will thus be seen that when two of the pawls have been dis-engaged from the ratchet wheels the opposite two pawls will be in position to effect the raising of the hollow screw-threaded bolt 331 and when the opposite set of pawls have been dis-engaged the engaging set of pawls will operate to effect a lowering of the hollow screw-threaded bolt.

Assuming that the pawls are, as shown in dotted lines in Fig. 56, withdrawn for the purpose of elevating the hollow screw-threaded bolt 331 the handle of the lever 336 will be swung about the hubs 334, as shown in dotted lines in Fig. 56, permitting the pawls 337 to engage the ratchet wheels 332 and rotate them in the direction for elevating the hollow screw-threaded bolt. In bringing back the handle of the lever 336 the pawls 337 will slip over the ratchet teeth and engage another tooth for the next movement. A cross-bar 344 connects the handles of the levers 336 so that they will move in unison. By this construction it will be seen that the elevation and lowering of the upper press-roll may be conveniently effected from either side of the machine and in an even and efficient manner. Springs 345 are interposed between the bearings of the upper press-roll and suitable follower plates 346 positioned upon the lower end of each of the hollow

screw-threaded bolts 331. The manipulation of the mechanism just described will increase or decrease the tension upon this spring 345 and thereby permit the upper press roll to yield in accordance with the 70 adjustment.

Bolts 347 pass through the hollow screw-threaded bolts 331 being at their lower ends screwed into the bearing and at their upper ends provided with locking nuts 348. 75

As will be hereinafter more particularly described the hollow press-rolls have a profile peculiarly adapted for carrying through the fabric and forming it so that the resultant product may be scored or indented 80 buttons of clay surrounding the junctions of the wires. It is necessary that the press-rolls having relative profiles shall be so adjusted that the formations upon the surfaces which form the profiles may be in exact 85 register. For this purpose I have provided a circumferential adjusting device which is illustrated especially in Figs. 35, 36, 59 to 63. Secured to the web of the driving gear wheel 247 of the upper press-roll (Fig. 36) 90 is the circumferential adjuster shown thus as a whole at 349. The adjuster comprises essentially a hub 350 with an extending flange 351, the hub being journaled on the stub shaft 248. A strap 352 passes across 95 the face of the adjusting mechanism, as shown in Figs. 59 and 60, and also in Fig. 40. It is in effect a flange strap inclosing the hub and other parts or a strap with right-angle arms or a U-shaped strap, 100 being secured, as indicated, by one of the arms to the flange and by the other arm to the hub. The strap is also indicated in Figs. 61 and 62 though but a part of the strap appears in those figures. In the face 105 or flange part of the adjuster are two sets of slots, one larger than the other, 353, 354. Through the larger slots 354 extend posts 355 which are secured to the web of the gear-wheel of the upper press-roll. These 110 posts receive a threaded eye-bolt 356 and the thread of the eye-bolt is engaged by a threaded bolt 357 having a squared end 358 to permit the application of a wrench. The bolt 357 has near its head an opposing pair 115 of collars 359 which embrace the side of a member 360 whose upper part is journaled by the longer arm of the strap and whose lower part is journaled in the flange or body of the adjuster. The member just described 120 has a pocket or an opening 361 in one side as shown in Fig. 62. Fitted in this pocket, in effect, is the operating bolt 357. In Fig. 62 at the right-hand is shown a pin 362 secured in the extending arms of the member 125 360 to prevent misplacement of the bolt 357. Through the smaller set of slots 353 extend bolts 363 which are in effect set screws for securing the adjuster once the adjustment is 130 made. In brief, the set screw 363 shown in

- detail in Fig. 63 is loosened, then a wrench or other tool is applied to the operating head of the bolt 357. When the bolt is rotated the threaded end engages the corresponding thread of the eye-bolt 356 which in turn draws upon the upright post 355 so as to bring a leverage upon the web of the gear-wheel. The gear-wheel, however, being locked by its connection with the other gear-wheels and the adjusting device being keyed to the shaft every such operation will result in the rotation of the upper press-roll through the shaft by which the adjuster is connected. By this means in connection with the other described adjusting means I can with the greatest nicety position the profile of the upper press-roll so that it will precisely register with the profile of the lower press-roll.
- 20 I provide a sidewise adjustment for the bearings of the lower press-roll as indicated in Figs. 32 and 54 and illustrated in Fig. 70. In Fig. 70 are shown set screws 364 passing through the frame and engaging extensions 365 which pass through slots in the inner parts of the skeleton frame and which in an obvious manner may be nicely adjusted sidewise in either direction.
- 30 I provide also for a nice lateral adjustment of both press-rolls which enables a final perfect alinement or register of the profiles of the two rolls by means of screw threads 366 on the journal heads of the rolls which take into corresponding nuts 367 as illustrated, for example, in Figs. 36, 40 and 56.
- 35 There are two other adjustments on the machine which require description.
- 40 In connection with the feeding roller 240 I have provided a duplicate of the circumferential adjuster which I employ with the press-rolls. This would appear in Fig. 32 but that for convenience of illustration it has been removed and shown in a separate Fig. 33 on the same sheet and is there numbered 368 and is shown as lying between the bracket 238 and the gearing, and journaled on the shaft 235.
- 50 Inasmuch as its operation is identical with that of the circumferential adjuster for the press-rolls it is not necessary to here describe this adjuster except to say that by its operation the feeding roller is brought into precise register with the press rolls above and that the feeding roller is also arranged with reference to the length of wire fabric coming over from the drum shaft 40 in accordance with the measured arrangement of the several parts to which reference has 60 heretofore been made.
- 65 In Fig. 32 I have also shown the driving arrangements but have reserved for a separate figure, Fig. 34, on the same sheet, an illustration of a device by which I may disconnect the two parts of the machine

rapidly and readily. I have shown in that figure the pinion 3 and the bearing 206 and the shaft 207. The pinion 3 is shown as having set into its sides two bearing faces 369. The shaft 207 is threaded as shown 70 and on this thread and taking against one of the bearing faces is a nut 370. When this nut is screwed up tightly against the pinion the opposite face 369 will abut against a shoulder on the shaft and the pinion be 75 secured to the shaft. When the nut 370 is released, on the contrary, the connection with the weaving part will be broken and the press will run alone, as may be at times desired.

80 I have also illustrated a desirable feature in oil cups which are of a familiar form and will require but a brief description. They are applied so as to oil the surface of the two press-rolls, the cup of the upper one 85 being illustrated at 371 and shown as bearing within it a roller which obviously turns in the oil and supplies the surface of the opposing press-roll, its position and pressure being governed by a weighted lever 90 372. A similar oil cup for the lower press-roll is designated by the numeral 373, its weight being numbered 374.

At 375 in Fig. 32 I have shown the attachment for an indicator and alarm and 95 have shown them in place in Fig. 35, but I have not specifically illustrated the indicator as any suitable one may be used.

100 In Figs. 64 to 69 I have brought together on the same sheet illustrations of the profiles of the press-rolls, the resulting product, etc.

I have shown the upper press-roll in relative position on the sheet and the lower press-roll below and have indicated by dot 105 and dash lines where the lines of wires are introduced between these figures I have shown, partly in section, the two rolls working together and drawing the wire fabric between them. The initial profile of the 110 surface of the two rolls is substantially the same. That is, they are grooved circumferentially and transversely leaving between the grooves relatively elevated portions 376. In the upper press-roll I have set in line 115 with the transverse center of these elevated portions a series of pins 377 with triangular heads. These pins, in fact, set in the center of what may be termed the circumferential grooves of the upper press-roll. Their 120 heads or the apex of the pyramid formed by the head reaches practically to the line of the surface of the outer periphery of the roll. A groove is formed in the top of each pin to receive the corresponding warp wire. 125 In the lower press-roll I put pins 378 similarly and I also put alternating with the positions of these pins another set of pins 379 which I may be said to have placed in the grooves which run in line with the axis 130

of the roll. There are then approximately twice the number of pins in the lower press-roll than there are in the upper press-roll. These pins 379 in the lower press-roll have 5 also the wire slot and at one side of the wire slot have a projecting hook 380 which engages the weft wire to draw the wire fabric through between the cylinders as plainly shown in Fig. 65. This provision not only 10 insures the certain feeding of the wire fabric but it serves also to draw that wire fabric through in a manner which will insure tightly placing the weft wires in the fabric. As the two cylinders turn the hooks 380 15 will project into corresponding groove spaces in the upper press-roll.

In the upper press-roll at selected spots are formed depressions 381, as shown circular, which lie between two of the pins on the 20 line of the warp wire. As the wire fabric and clay are formed between the press-rolls these depressions form corresponding buttons or circular projections 382 on the fabric so that in this wise each length of the fabric 25 is marked. There may be also a corresponding alarm which will ring on the indicator and I provide that this indicator will so operate to show how many of these lengths are formed. By this provision the operator 30 is enabled to tell precisely where to cut off the fabric so as to have exactly so many lengths or exactly a length wound up on the reel.

Operation.

35 In the preceding description of the various parts of the machine I have defined their operation. I will now review the general operation of the whole machine, pointing out 40 at the same time some of the advantages now more apparent after a reading of the description and operation of the several parts.

Weft wires of the proper gage may be 45 arranged on a reel frame which I have especially provided for this machine, but which it is not necessary here to describe. The wires are then led into the machine, as illustrated in Fig. 1, under the guide rollers 31, 50 32, up to the drum shaft 35 and then are threaded in the customary way through the perforations or eyes of the heddles of the frames 21, 22. Thence they go to the drum shaft 40, which, as described, is rotated in 55 unison with the other parts of the machine, and which feeds the fabric to the press part of the machine.

Power is imparted to the machine through the pulley 200 (Figs. 32, 35, 36-38). Within 60 the pulley 200 is the expanding clutch 208 which has formed integral with it a beveled gear wheel 209 so that when the clutch engages the pulley 200 the beveled gear wheel 209 will be rotated, driving the gear wheel 210 which rotates the shaft 207. This shaft

in turn rotates the pinion 3 which drives the intermediate gear wheel 4 on the shaft 5 and thus through the gear wheel 6 and the friction disk 8 rotates the power shaft 7 of the weaving part of the machine. The 70 rotation of the shaft 7 through the pinion 10 operates the gear wheel 11 which rotates the shaft 12. The rotation of the shaft 12 operates cams 13 and 14 (Figs. 1 and 3). The cams 13 and 14 alternately reciprocate 75 the levers 17 and 18 pivoted at 15 and thus oppositely operate the frames 21 and 22 of the harness which carries the warp wires.

As the frames 21 and 22 of the harness reciprocate the ranks of wires they carry 80 form the shed through which the shuttle is to be passed. During the operation as the wires approach each other there is a slack in the ranks of the wires and this slack is taken up by a mechanism (see Figs. 1 and 85 4) for carrying outward the drum shaft 35 through the disk 41, the conical cam 42, the roller 43, and the lever 44 operating the bracket arms 37 on one side and transmitting the effect through a rod 49 across the machine to the bell-crank lever 50. The effect is to carry out the drum shaft as the wires slacken so that they are kept taut.

Through the shed formed by the ranks of the warp wires the shuttle 52 (Figs. 1-10) 95 is thrown back and forth, passing in the usual manner first through one shed and then through the opposite or succeeding shed formed by drawing down what was the upper rank of wires and forcing up what was the 100 lower rank of wires, thus introducing the weft wire into the fabric in the usual manner. The shuttle travels across the inclined frame 53 carrying with it on the bobbin 105 spool 58 the weft wire, the bobbin spool being automatically braked in accordance with the requirements of the operation. When the shuttle nears one end of the machine it strikes the weighted buffers 84 (Figs. 6, 12-15) which swing upon the pivoted arms 110 83. The shuttle is now caught by the latch 93 (Figs. 3, 4, 6, 11) which engages a catch 92 on the shuttle to prevent a rebound and hold it momentarily at the end of the throw. Immediately following this placing of the 115 shuttle, the cam 80 operated by the shaft 81 if the shuttle be at that side, or a similar cam on the shaft 810, if the shuttle be at the other side of the machine, wipes an end of the shuttle and forces it out against the 120 projection 78 at the bottom of a swinging arm 64 or 65, depending upon at which end of the machine the shuttle is operated, and through connections with the link 62 distends the spring 61. As the shuttle is moved 125 out to effect this distention of the spring the catch 92 will, of course, be removed from the latch 93. The latch 93 is now moved out of the path of the shuttle through the action of the cam 103 upon the lever arm 95. 130

The path is now free for the shuttle and as soon as the cam 80, for example, passes from the rear of the shuttle after having forced it out the distended spring 61 comes 5 into operation and through the arm 64, for example, sweeps the shuttle forward along its path to the other end of the machine where the operation is repeated.

As the shuttle speeds across the machine 10 driven by a power independent of the operating power, the annular brake 104 is brought into operation by the cam 107 on the shaft 98, operating the lever 108 which engages the screw-threaded rod 110 whose 15 forked end operates an arm 111 raising the bar 112 as the roller 113, pivoted on the shuttle, strikes it (Fig. 16). The effect of this is to raise the shaft 116 and thereby depress the spring plate 117, pressing the annular brake 104 against the ring 105 operating directly upon the spool of the shuttle 20 (Fig. 7). I provide also, as described, for an additional braking action through the part 120, the purpose being to regulate the 25 tension of the wire in accordance with the requirements.

The weft wires pass out the shuttle through an opening or slot 127 across the roller 128, thence around the roller 129 or 30 130, depending upon the position of the shuttle in the raceway (Fig. 8). These rollers, as described, have devices permitting them to yield so that the strain on the wire when the shuttle is first struck is taken up. 35 It is this weft wire which is taken by the reed 142 and packed into the end of the shed to complete the weave of the fabric. The teeth of the reed 132 sweep across the machine as the wire is stretched out.

40 As I have before shown I am enabled to throw the shuttle at the same speed whatever may be the speed of the machine or the number of reciprocations of the shuttle in a given time.

45 When I am running the machine rapidly there will be more reciprocations of the shuttle, and each reciprocation will be at the same speed. This, as I have shown, is important because it prevents the probability 50 of danger in the operation of the machine at high speeds. In such event, the shuttle is not thrown with greater force and therefore is not likely to be thrown out of the machine or through the opposing parts.

55 I have shown also that in the construction of my composite metal lath it is essential to construct the wire fabric with precision, and an important feature of this provision is the positive operation of the shuttle 60 after the end of its throw through the cams 80 and the described parts to provide the automatic braking of the bobbin at that time so as to positively draw upon the weft wire to tighten it and to properly pack it into place between the warp wires.

The reed 142, illustrated in Fig. 2 and elsewhere, and whose operations are detailed in Figs. 18-21, operates in conjunction with the shuttle. As the weft wire is drawn taut by the shuttle in its positive operation at the end of its throw the reed comes over and its teeth pack the weft wire into place while the outer arms 1420 of the reed carry over the wire so that it is looped into place about the specially devised teeth 75 of one of the wheels 139 or 140, depending upon which side of the machine the shuttle lies. The completed fabric then passes beyond the wheels 138, 139 onto the drum shaft 40 from whence it proceeds to the press part 80 of the machine.

I have heretofore described the construction and operation of the automatic checks by which the machine is governed so that unless those parts are set at each action of 85 the machine both parts of the machine will stop. These devices are illustrated generally in Figs. 1, 2 and 4, and in detail in Figs. 26-31.

In the regular operation of the machine 90 as the power shaft 7 turns, the cam 150 wipes against a roller head on the arm 152, so that it will be thrown in the direction indicated in full lines in Fig. 26. The lever 152 is connected at the bottom, as described, 95 to the slide bar 158. This slide bar carries a cylindrical bearing 160. When the rod 162 passes through this bearing, projecting as shown, for example, in Figs. 1 and 3, the effect of the forward movement of the slide 100 bar 158 would be to engage through this projection the rod 179 and throw that rod to disengage the clutch 208 and apply the brake in the driving pulley 200 and thus stop the machine. This, as I have described, 105 is the normal operation of the machine but for the automatic checking mechanism which is operated by the shuttle. The roller 168 lies in the path of the shuttle and as the shuttle sweeps along at the end of its 110 path its side wipes the roller 168 and then, through the shaft 170, link 171, the short shaft or pin 172 and the link 173, operates the arm 174 which is secured to and operates the shaft 175 and, through the rod 176, lifts 115 the flexible extension 167 withdrawing the projection 160 so that the slide bar 158 moves forward without effect upon the clutch governing rod 179. In the same manner the parts illustrated in Figs. 29-31 would 120 operate through the cam 151, the lever 153 and the connected parts, the governing rod 179, but for the action of the weft wire which, stretched across the machine, strikes the extending arms 178 and operates the 125 shaft 177 so that through the connected parts the projection 163 is drawn upward permitting the reciprocation of the slide bar 158 without effect upon the governing bar 179.

Thus, as long as the shuttle is making its proper reciprocation from side to side of the machine and as long as the weft wire is stretched across the machine and not broken, 5 the machine will operate. But at once upon any failure of the shuttle or the wire the machine will stop as a result of its normal operation.

It is assumed that the clay is properly 10 arranged in the feeding device illustrated in place in Figs. 32 and 35 and in detail in Figs. 46-53, and that heat has been applied to the rolls of the press part of the machine. It is also assumed that the various 15 adjustments of the rolls have been made so that the projections on the press roll are in perfect register and so that there is a proper relation between the feeding roller, the press rolls and the drum shaft 40 from 20 which the wire fabric is to be fed from the press part of the machine.

The feeding roller is adjusted by the circumferential adjuster which corresponds with an adjuster of the same kind illustrated 25 in Figs. 59-63 which applies to the upper press roll the adjustment which brings into register the profiles of the surfaces of the press rolls illustrated in Figs. 64-69, as heretofore fully described. The other adjustments 30 are also assumed to be carefully made as, for example, the proper positioning of the journals by the mechanism illustrated in Figs. 40, 54 and 55, the duplicate vertical adjustment which is also a yielding adjustment 35 for the upper press roll so that it may first be evenly placed as desired and yield if any hard substance passes between the two rolls, as illustrated in Figs. 32, 36, 40, 54-58, 70, a side-wise adjustment for the 40 bearings of the lower press roll as illustrated in Fig. 54 and in detail in Figs. 32 and 70, and a final nice lateral adjustment of both press rolls by the screw threads on the journal heads as illustrated, for example, 45 in Figs. 36, 40 and 56. It is assumed also that the driving parts of the two machines are connected though they may be at any time rapidly and easily disconnected, as illustrated in Figs. 32 and 34, by the connection 50 between the bearing faces 369 and the nut 370.

As the fabric comes from the weaving part of the machine, it is accurately organized with respect to the location of the 55 crimps and the weft wires, but it is not accurately organized with reference to the lateral arrangement of the warp wires. The wire fabric runs over the drum shaft 40 and is carried down to the feeding roller 240 (Figs. 32, 46). The relative arrangement of the feeding roller enables the machine to get a firm grip on the wire fabric and at the same time economizes the space because 60 projecting above it is the clay feeding device 299. The feeding roller 240 is pro-

filed with exact reference to the ultimate composite metal lath. Its pyramidal projections enable the surface apexes to enter the mesh of the wire fabric and as the wire fabric is drawn tightly about the periphery 70 of the feeding roller and the bases of the projections, each mesh is straightened out and the whole fabric presents then a series of exact squares in which the weft wires are tightly placed. In fact, one of the essentials of this operation is that the weft wires 75 shall have been tightly placed so that there may be no fault in this patterning of the wire fabric first by the feeding roller and then by the press rolls to which the fabric 80 now goes. The now accurately formed wire fabric is caught by hooks 380 of the lower press roll which take against the side of the weft wires and draw the wire fabric in between the press rolls as illustrated for example 85 in Fig. 55. At the same time, clay or other material is fed down the platform 299 so that it enters between the heated press rolls along with the wire fabric. The result is that the wire fabric is enveloped by the 90 clay or in other words, the wire fabric is embedded in the clay. It comes out horizontally on the opposite side of the press rolls patterned reversely from the patterns of the two press rolls. It now passes between the grooving or scoring rolls illustrated 95 in Figs. 32, 35, 36, 41, 70, and thence under the cleaning roll 259, detailed in Fig. 42, coming out from them to the winding reel 267 (Figs. 35, 43, 70), from whence it 100 may be taken in rolls to the burner to have the buttons of clay covering the intersections of the wires, converted into buttons of brick.

As I have before described, I find it necessary or advantageous to heat the press rolls and to heat the scoring and the cleaning rolls. This I do by a mechanism which applies steam or other medium as the rolls 105 rotate and which serve at the same time as safety valves when there is an undue pressure, (Figs. 40, 44, 45, 70).

I also, as previously described, provide for oiling the surface of the two press rolls by automatic oiling devices, 371, 374 (Figs. 115 32, 36, 70).

I provide also for an initial winding of the fabric on a reel 267, by hand. The fact that the product is grooved enables me to slide the reel on the fabric, the slot 2670 120 running in along the groove but the clay projections preventing the fabric from being drawn out laterally through the slot (Figs. 35, 43, 70).

I have before referred to the necessity of 125 constant coördination between the weaving part of the machine and the press part of the machine and this coördination and unit arrangement is necessary or advisable to bring out finally upon the reel 267 a prod-

uct in which these buttons of clay or other material shall precisely fit the intersection of the warp and weft wires.

As I have before suggested, it is even pro-

- 5 vided that the distance between the top central line of the drum shaft 40 and the engaging point of the feeding roller 240 shall be a multiple of the unit measurements of the wire fabric, so that the feeding rollers 10 may precisely engage the openings in the fabric to lay out the wires as they go to the press rolls. When the wires go to the press rolls, it will be observed that as they fit into place the drop or kick in the wires will fit 15 exactly into the grooves arranged to receive the wires so that the whole wire fabric is firmly held in place, first by the feeding roller and then even more accurately and firmly by the press rolls.

20 I have also illustrated in Fig. 32, as secured, to the side of the machine and operated from the shaft 235, an indicating device which may in accordance with familiar precedents be governed by the passing of 25 the wire fabric upon the winding reel, a feature not necessary to further illustrate or describe.

In the previous description I have pointed out the provision for marking the fabric 30 as at the point 381, Fig. 64, to indicate the amount being supplied to the reel independently of the ordinary indicating mechanism I have suggested.

I claim,—

- 35 1. In a machine for making a composite metal lath of the character described, the combination with means for pressing together clay or other material and a wire fabric so as to embed the wire fabric in the 40 material, of means for feeding the wire fabric and means for feeding the clay or other material separately to the pressing point.

2. In a machine for making a composite lath, the combination of means for drawing 45 forward a meshed fabric, means for flowing a layer or strip of clay or similar material to meet the fabric, and means for pressing the two together so that buttons of clay are formed upon the fabric at the 50 intersection of the strands of the fabric.

3. In a machine for making a composite metal lath of the character described, the combination of means for feeding a plastic material and means for feeding a wire fabric to a meeting point, with means for embedding the wire fabric in the material and means for then removing the surplus material to make the lath flexible.

4. The combination of means for feeding 60 clay or other material and means for feeding and for determining the structure of a wire fabric, with means for pressing together the clay or other material and the wire fabric to embed the wire fabric in the 65 material.

5. In a machine for making a composite lath, the combination with means for feeding a fabric, means for feeding clay or other material, means for combining the clay or other material and the fabric, and 70 means for keeping the fabric under tension until the clay or other material is applied.

6. In a machine for producing a composite metal lath of the character described, the combination of means for weaving a wire 75 fabric with means for applying a plastic material to embed the wire fabric in the plastic material.

7. The combination with means for forming a wire fabric of quadrangular mesh, of 80 means for applying buttons of clay or other material at the point of junction of the warp and weft wires.

8. The combination with means for forming a wire fabric, of means for applying a 85 coating of clay or other material to each side of the wire fabric and means for indenting or scoring the clay or other material.

9. The combination of means for forming 90 a wire fabric, means for applying a coating of clay or other material to the wire fabric and means for removing parts of the clay or other material along lines which will render the product flexible. 95

10. The combination with mechanism for weaving a wire fabric, of mechanism for drawing the wire fabric from the weaving mechanism and applying to the junctions of the warp and weft wires buttons of clay 100 or other material.

11. The combination of mechanism for weaving a wire fabric, feeding means for taking the wire fabric from the weaving mechanism, press-rolls carrying the wire 105 fabric between them, means for feeding clay or other material between the press-rolls at the same time the wire fabric is passing through them, and means for treating the combined wire fabric and clay or other 110 coating to finish the product.

12. The combination of means for weaving a wire fabric, feeding mechanism for taking the wire fabric from the weaving mechanism, press rolls and means for feeding the wire fabric between them, feeding 115 mechanism for carrying clay or other material between the press-rolls at the same time the wire fabric is passing through, cutting or grooving rollers and punching rollers for 120 completing the product.

13. The combination with mechanism for weaving a wire fabric, of mechanism for coating the wire fabric, a common driving mechanism and means for automatically 125 stopping the operation of both mechanisms when the shuttle or the wire it feeds fails of complete operation.

14. In a machine for producing a composite metal lath of the character described, 130

- the combination of a mechanism for weaving a wire fabric, means for feeding the wire downwardly then upwardly to press-rolls, and means for feeding in clay or other material to the press-rolls from above. 5
15. Means for feeding a meshed fabric, means to receive the fabric and maintain relation of the meshes, means for feeding plastic material upon the fabric and means for applying buttons of the plastic material on each side at the intersection of the strands of the fabric. 10
16. In a machine for producing a composite metal lath of the character described, 15 the combination of a pair of opposing rolls provided with appliances for engaging and drawing between them a wire fabric and means for feeding to the rolls layers or strips of clay or other material. 20
17. A pair of press-rolls relatively patterned to receive a wire fabric and draw the fabric between the rolls, and means for at the same time feeding in clay or other material between the rolls. 25
18. A pair of press-rolls for applying a plastic material to a wire fabric which are relatively grooved and formed to receive the mesh of the wire fabric and have means to engage the wire of the fabric to forward 30 the fabric, in combination with means for feeding clay or other material to the press rolls. 35
19. The combination with means for weaving a netting of wire, of means for forming the meshes to a precise standard unit and maintaining that form while the netting receives an application of clay or other material. 40
20. The combination with a pair of press-rolls for applying a plastic material to a wire fabric, of means for feeding to the press-rolls the wire fabric and means for feeding to the press-rolls the plastic material, means for treating the substance so 45 formed to render it flexible, and a winding reel operated in unison with the forming parts. 50
21. The combination with a pair of press-rolls for applying a plastic material to a wire fabric, of means for feeding to the press-rolls the wire fabric and means for feeding to the press-rolls the plastic material, and means for treating the substance so formed to render it flexible. 55
22. In a machine for producing a composite metal lath of the character described, the combination of a weaving mechanism for forming a quadrangular mesh wire fabric with mechanism for enveloping the wire 60 fabric in a plastic material, the two mechanisms being relatively arranged with reference to the units of the product. 65
23. In a machine for producing a composite metal lath of the character described, the combination with mechanism for weav- 70
- ing a wire fabric comprising a delivering drum-shaft of press-rolls and adjunctive devices for coating the wire fabric, and a feeding roller for conveying the fabric from the drum-shaft to the press-rolls, the feeding roller and the press-rolls being arranged with reference to the units of the wire fabric and the distance between the delivery point of the drum-shaft and the receiving point of the feeding roller being multiples 75 of the units. 80
24. The combination of a weaving mechanism for making a wire fabric, with a mechanism for coating the wire fabric with clay or other material, the parts being arranged so that the relation of the fabric on the weaving mechanism to the fabric in the coating mechanism is coördinated. 85
25. The combination of a wire-netting mechanism, a mechanism for coating the wire fabric with clay or other material, a driving shaft common to the two mechanisms, a driving pinion on the shaft, and a friction clutch nut screwed on the shaft and adapted to lock the pinion to the shaft. 90
26. The combination of a pair of press-rolls and a feeding roller to engage a wire fabric and feed it between the press-rolls and adjusting means to relatively register the surfaces of the press-rolls and adjusting means to register the feeding roller in accord with the press-rolls. 95
27. The combination of a pair of patterned press-rolls with means for vertically adjusting them, means for circumferentially adjusting them, and means for adjusting them sidewise and means for adjusting them laterally. 100
28. The combination with a press-roll of means for adjusting the press-roll simultaneously from both ends comprising a threaded screw bolt, a pawl and ratchet mechanism to operate the screw bolt on each side, an arm connecting the pawls to set them, and a connecting operating handle. 105
29. The combination with a press-roll, of means for adjusting the press simultaneously from both ends comprising an adjusting device having a threaded rod, a ratchet head for the rod, a pair of pawls, each pawl having a dog, a cam whose surfaces engage the dogs from opposite sides, and means for shifting the cam to determine which pawl shall be operative. 115
30. The combination with a pair of press-rolls and means for simultaneously feeding in the wire fabric and a coating for the wire fabric, of a pair of cutting rolls for grooving the fabric. 120
31. The combination with a pair of press-rolls, of means for feeding in the wire fabric and means for also feeding in a coating for the wire fabric, and a punching roll for removing the surplus material from between the meshes of the fabric. 125
- 130

32. The combination with a pair of press-rolls, cutting rolls and a cleaning roll, of means for heating the interior of the several rolls.
- 5 33. The combination with cutting rolls and cleaning rolls of means for heating the several rolls from a common source.
34. The combination with a pair of press-rolls adapted to receive between them a wire fabric, of an inclined feeding chute adapted to feed clay or similar material between the press rolls and means for adjusting the feeding device.
- 10 35. The combination with means for receiving a woven fabric with means for feeding strips of clay or similar material upon the fabric, comprising side-bearing plates, shafts journaled in the plates, means for rotating a shaft, revoluble sleeves on the shafts and division plates separating the sleeves on alternate shafts.
- 15 36. A press-roll having intersecting grooves in its face and pins with wire-guiding slots in their heads inserted along the lines of the wires.
- 20 37. A press-roll having grooves in its face forming relative pyramidal elevations and a set of pins with triangular heads between pairs of the projections.
- 25 38. A press-roll having grooves in its face, and pins having wire-engaging hooks set in its face.
- 30 39. A pair of press-rolls having relatively arranged projections and depressions to pattern the product and provisions for guiding wires between them.
- 35 40. A pair of rolls having relatively arranged projections and depressions, and pins with pyramidal heads set into the rolls to determine the shape of the product and the line of the wires.
- 40 41. A lower press-roll patterned to impress the product and having a series of projecting pins to engage a wire fabric and feed it about the roll.
- 45 42. The combination with a weaving mechanism for producing a wire netting and a press mechanism for receiving the wire netting from the weaving mechanism and applying to it a coating of clay or other material, of a common power device and controlling means comprising a clutch and a brake and means for operating the brake when the clutch is released.
- 50 43. In a weaving mechanism, the combination of a race-way, a shuttle on which the race-way travels, a spring, swinging arms on each side of the machine to which the spring is connected, and a cam adapted to wipe against the end of the shuttle to tension the spring.
- 55 44. In a weaving mechanism, the combination of a shuttle, means for operating the shuttle to throw it alternately across the machine and back, comprising a swinging arm on each side of the machine and weights carried by the arms, with buffer devices to receive the first impact of the shuttle.
- 60 45. In a weaving mechanism, an inclined race-way, a shuttle traveling on the inclined race-way, and a pair of weights having buffers lying in different horizontal planes and adapted to receive the impact of the shuttle.
- 65 46. A weaving mechanism having a shuttle-carrying arm, a swinging buffer, comprising weights carrying the buffer pads and an adjustable buffer to receive the shuttle-carrying arm.
- 70 47. In a weaving machine, the combination of a shuttle, a roller secured to the frame of the machine and lying in the path of the shuttle, and connecting devices leading from the roller and governing the operation of the parts to prevent the stopping of the machine.
- 75 48. In a weaving or wire-netting machine, the combination with a shuttle of a spring-actuated means for operating the shuttle, and means for moving the shuttle outwardly after the throw of the spring to tension the spring for a return throw of the shuttle.
- 80 49. In a weaving or wire-netting machine, the combination of a shuttle and spring-actuating means, a latching device and means for releasing the latch and means operating at the same time to give the shuttle an additional movement to tension the spring.
- 85 50. In a weaving mechanism, a reed having a series of teeth to fit between the warp strands and fingers for alternately engaging the weft strand coming from the shuttle, first on one side and then on the other, and a pair of wheels for receiving the weft strands and measuring their separation.
- 90 51. In a weaving mechanism, a reed for engaging the weft strand, means for operating the reed and toothed wheels which receive and space the weft strands when fed to them by the reed.
- 95 52. A weaving mechanism comprising a reed having a series of teeth which pass through spaces between the warp strands, each having a pair of side arms which alternately engage the weft strand coming from the shuttle and a pair of toothed wheels which alternately receive the weft strand.
- 100 53. In a weaving machine, the combination of a slide-bar controlling a clutch mechanism, a slide-bar having projections for engaging the clutch operating bar, a shaft having fingers which lie in the path of the weft strand as it is fed forward and connected with the device for operating the projections to remove them out of the line of the clutch operating bar.
- 105 54. In a weaving machine, the combination of a shuttle, a spring-actuated means

for throwing the shuttle, and a positively operating means for giving the shuttle a further throw to tighten the weft strand.

for imparting to the shuttle an additional movement, a reel in the shuttle, a brake for the reel, and means acting upon the brake 50 during the additional movement.

55. In a weaving machine, the combination of a shuttle, a spring-actuated means to throw the shuttle, means for holding the shuttle temporarily at the end of the spring throw, and means for then advancing the shuttle.

62. In a netting machine of the class specified, a shuttle, spring-actuated means for moving the shuttle to and fro, means for imparting to the shuttle an additional 55 movement, a reel in the shuttle, a brake on the shuttle consisting of a two-armed pivoted member, one end of which co-acts with the reel to be braked and the other end of which co-acts with an inclined race.

60 63. In a netting machine of the class specified, a shuttle, spring-actuated means for moving the shuttle to and fro, means for imparting to the shuttle an additional movement, a reel in the shuttle, a brake 65 adapted to hinder the turning of the reel, automatic means for bringing the brake into action during the said additional movement, and automatic means for taking the brake out of action at the beginning of the return 70 of the shuttle.

64. In a weaving machine, the combination with a shuttle and its operating mechanism, of means for stopping the machine at each action of the shuttle controlled by the 75 action of the shuttle and a weft strand feeding from the shuttle to prevent the operation of the stopping means while the machine is operating properly.

65. In a weaving machine, the combination of a race-way, a shuttle adapted to travel on the race-way, a shuttle operating means, a latch at each end of the race-way, means for releasing the latch and means for then giving an additional movement to the 85 shuttle against the resistance of the shuttle operating means.

In testimony whereof I have hereunto signed my name in the presence of two subscribing witnesses.

FRED'K NOSSAGK.

Witnesses:

E. BARMWATER,
E. J. JOCHEN.

5. In a weaving machine, the combination of a shuttle, a spring-actuated means to

throw the shuttle, means for holding the shuttle temporarily at the end of the spring throw, and means for then advancing the shuttle.

10 56. In a weaving machine, the combination of a shuttle, a race-way for the shuttle, a movable section at the end of the race-way, a pivoted arm projecting from the shuttle and connected to a brake on the shuttle, and means for raising and lowering the movable section to operate and release the pivoted arm.

20 57. In a netting machine of the class specified, a shuttle, spring-actuated means for moving the shuttle to and fro, locking means for preventing a return of the shuttle at the end of this to and fro movement, means for imparting to the shuttle an additional movement, and means for unlocking 25 the means preventing the return of the shuttle.

58. In a netting machine of the class specified, a shuttle, spring-actuated means for moving the shuttle to and fro, and combined means for imparting to the shuttle an additional movement and for tensioning the said spring-actuated means.

35 59. In a netting machine of the class specified, a shuttle, spring-actuated means for moving the shuttle to and fro, and compensating weights on freely oscillating levers compensating the impact of the shuttle.

60 60. In a netting machine of the class specified, a shuttle, spring-actuated means for moving the shuttle to and fro, means for imparting to the shuttle an additional movement, a reel in the shuttle, and means for hindering the turning of the reel during the said additional movement.

45 61. In a netting machine of the class specified, a shuttle, spring-actuated means for moving the shuttle to and fro, means
